UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

CAR-DOOR-LOCKING MECHANISM.

1,417,495.

Specification of Letters Patent. Patented May 30, 1922.

Application filed December 27, 1921. Serial No. 525,104.

To all whom it may concern:

Be it known that I, ARGYLE CAMPBELL, a citizen of the United States, residing at Chicago, in the county of Cook and State of Illinois, have invented a certain new and useful Improvement in Car-Door-Locking Mechanisms, of which the following is a full, clear, concise, and exact description, reference being had to the accompanying drawings, forming a part of this specification.

This invention relates to improvements in car door locking mechanisms.

One object of the invention is to provide a simple, efficient and rugged locking mechanism for doors of a dump car.

A specific object of the invention is to provide a locking mechanism for doors of a dump car known as twin door type.

In the drawing forming a part of this specification, Figure 1 is a side elevational view of a portion of a twin door type of dump car showing my improvements in connection therewith, the twin doors being in closed locked position. Figure 2 is a vertical, sectional view taken transversely of the car and corresponding substantially to the line 2-2 of Figure 1. And Figure 3 is a view similar to Figure 1 but illustrating the condition of the locking mechanism when one of the doors is in open or partly open position, in order to better illustrate certain details of the construction.

In said drawing, I have only illustrated sufficient of a dump car of the twin door type necessary to an understanding of my invention, it being evident that the improved locking mechanism will be duplicated for each set of twin doors and also that the locking mechanism may be applied to dump cars of different type.

In said drawing, portions of the side walls of the car are indicated at 10, the same being converged inwardly for a distance as indicated at 11 near their lower ends and thence extended down vertically as indicated at 12. The vertical sections 12 are of more or less triangular outline, as viewed in side elevation and shown in Figure 1, the lower sloping edges of said vertical sections 12 being preferably reinforced by plates 13 riveted thereto. The discharge opening is adapted to be closed by two doors 14-14, the latter being pivoted to suitable hinge butts 15-15 to adapt the doors to swing

about axes extending transversely of the car, the doors swinging oppositely and having their free edges meeting when the doors are in closed position, as clearly indicated in Figure 1. Each of the doors is braced or reinforced along its free edge by an inverted U or channel shaped brace 16 riveted thereto and terminating within the flanged side edges 17-17 of the door. The side flanges of the channel or U brace have their free edges outturned or oppositely extended as indicated at 18-18.

To lock the doors in closed position, I employ the following arrangement, it being understood that the arrangement is duplicated on each side of the car. On each side of the car, I employ what may be termed a twin bracket designated generally by the reference character A. Each bracket A is formed on the top thereof with two flange sections 19-19 integrally formed and sloping oppositely upwardly from the center to correspond to the slope of the lower edges of the vertical sheets 12, said flange sections 19 being riveted to the sheet 12, as shown in Figures 1 and 2. Below the flange sections 19, the bracket A is formed with three dependent heavy arms B, C and D. The arm B is centrally located opposite the meeting line of the free edges of the doors and the other two arms C and D are symmetrically disposed with the central arm B but on opposite sides thereof. The arms C and D extend in a general direction perpendicular to the main plane of the corresponding door when the latter is in closed position. Each of the arms B, C and D is outwardly offset from the flange sections 19 as indicated best at 20 in Figure 2 so as to provide the necessary clearance for the side edges of the door and allow the main portions of the latter to abut snugly against the lower edges of the reinforced sheets 12, as will be clear from an inspection of Figure 2. Each of the arms C and D, clear at its bottom end, is formed with an outwardly extended shelf or ledge 21, the upper face of which extends parallel to the plane of the corresponding door when the doors are in closed position.

The central arm B of the bracket A, at its bottom end, is formed with oppositely disposed sets of perforated flanges or ears 22-22, the same extending parallel to the main plane of the corresponding door when

the latter is in closed position and accommodating therebetween a locking lever 23. The levers 23 are pivotally connected to the bracket A by suitable means such as the 5 bolts 24. With this construction, it will be observed that the lock levers 23 are adapted to swing in planes parallel to the planes of the respective doors when the latter are in closed position and to have the free ends of 10 said levers swung into position over and rest upon the corresponding shelves or ledges 21-21.

The lock levers 23 are adapted to be held in their operative or closed position by latches 15 25 pivotally supported from the corresponding arms C and D, the free ends of the latches 25 swinging outside of and against the respective lock levers 23. The free end of each latch 25 may be laterally enlarged as indicated at 25^a in Figure 2 for the twofold purpose of increasing the weight of the free end 20 and to provide a suitable section to be hit with a bar in releasing the mechanism.

On each door, at each side thereof and 25 within the channel brace, is secured a bracket casting designated generally by the reference E. Each bracket casting E is formed with a top flange 26 riveted to the web of the channel brace and with a flange 27 30 riveted to the flange of the brace remote from the free edge of the door. Each bracket casting E is further provided with a vertically extending flange as indicated at 28 immediately inside the side flange 17 of the 35 door and from the lower portions of the flanges 27 and 28 and below the door flange 17, is extended outwardly horizontally an integral arm or bar 29. The arms or bars 29 are so positioned that, when the door swings 40 to closed position, the arms pass up into the recesses indicated at 30 which are defined between the pairs of depending arms of the brackets A. When the arms or bars 29 are in their uppermost position, that is, with the 45 doors closed, the lock levers 23 are swung beneath them, thus securely locking the doors in closed position, as will be evident.

It will be seen that the arrangement shown and described can be manufactured, sold and 50 applied at comparatively small cost; the mechanism may be operated with ease and without the use of any special tools; there are no delicate or weak parts likely to fail or get out of order; and the mechanism insures 55 the doors being maintained in fully closed position even under full load.

I have herein shown and described what I now consider the preferred manner of carrying out the invention, but the same is merely 60 illustrative and I contemplate all changes and modifications that come within the scope of the claims appended hereto.

I claim:

1. In a dump car having a pivoted door, 65 the combination with a bracket secured to a

fixed part of the car adjacent an edge of the door when the latter is in closed position; of a bar rigid with the door and projecting from said edge in line with said bracket; a locking lever pivotally supported on said bracket to swing against said bar on the under side of the latter; and means for holding 70 said lever in locked position.

2. In a dump car having a pivoted door, 75 the combination with a bracket secured to a fixed part of the car adjacent an edge of the door when the latter is in closed position; of a bar rigid with the door and projecting from said edge in line with said bracket; and a locking lever pivotally supported on 80 said bracket to swing against said bar on the under side of the latter, said bracket having a supporting ledge on which the free end of said lever rests when in locked position.

3. In a dump car having a pivoted door, 85 the combination with a bracket secured to a fixed part of the car and having separated arms projecting substantially perpendicular to the plane of the door past one edge of the latter; of a bar rigid on said door projecting from said edge and movable to a position between said arms; and a locking member arranged to extend from one arm to the other and be supported thereby and lock said bar between said member and bracket. 90

4. In a dump car having a pivoted door, 100 the combination with a bracket secured to a fixed part of the car and having separated arms projecting substantially perpendicular to the plane of the door past one edge of the latter; of a bar rigid on said door projecting from said edge and movable to a position between said arms; and a lever pivoted to one of said arms and swingable in a plane substantially parallel to the plane of the 105 door to engage said bar and hold the door in closed position.

5. In a dump car having a pivoted door, 110 the combination with a bracket secured to a fixed part of the car and having separated arms projecting substantially perpendicular to the plane of the door past one edge of the latter; of a bar rigid on said door projecting from said edge and movable to a position between said arms; and a lever pivoted to 115 one of said arms and swingable in a plane substantially parallel to the plane of the door to engage said bar and hold the door in closed position, the other of said arms having a supporting ledge for the free end 120 of said lever when the latter is in operative position.

6. In a dump car having a pivoted door with the free edge thereof adapted to swing downwardly when opening, the combination 125 with a bracket secured to a fixed part of the car and having a portion extending across the side edge of the door when the latter is in closed position; of a projection rigid with the door and extending from said side 130

thereof; a lock lever pivoted to said portion of the bracket adapted to swing to a position on the under side of said projection, said bracket having a supporting ledge for 5 the free end of the lever.

7. In a dump car, having a pivoted door with the free edge thereof adapted to swing downwardly when opening, the combination with a bracket secured to a fixed part of 10 the car and having a portion extending across the side edge of the door when the latter is in closed position; of a projection rigid with the door and extending from said side thereof; a lock lever pivoted to said 15 portion of the bracket adapted to swing to a position on the under side of said projection, said bracket having a supporting ledge for the free end of the lever; and a latch pivotally supported on said bracket adapted to 20 swing against the outer side of said lock lever to thereby retain it in operative position.

8. In a dump car, the combination with a pivoted door; of a brace secured to the 25 under side of the door, said brace being of substantially inverted U cross section; a bracket casting secured within said brace and having an integral arm projecting beyond an edge of the door; and means supported from a fixed part of the car cooperable with said arm to hold said door in 30 closed position.

9. In a dump car, the combination with a pair of pivoted doors adapted to swing 35 oppositely and having their free edges meeting when in closed position; of a bracket

secured to a fixed part of the car opposite the line of meeting of said free edges of the doors; a projection rigid with each door; and a pair of independently operable lock- 40 ing elements supported from said bracket and cooperable with the respective door projections to lock the doors in closed position.

10. In a dump car, the combination with a pair of oppositely swinging doors having 45 their free edges meeting when in closed position, each door having arms rigid therewith projecting beyond the side edges thereof and adjacent the free edge of the door; of a pair of brackets secured to fixed portions of the car opposite the ends of the line of meeting of the free edges of the door, each of said brackets having a central and two side arms projecting across the side edges of the doors; a pair of lock levers pivotally mounted on said central arm of each bracket and adapted to swing under the respective projecting arms from the doors; supporting shelves on each of the side arms of each bracket upon which the free ends of 60 the respective lock levers are adapted to rest when in operative position; and means for retaining said lock levers in operative position.

In witness that I claim the foregoing I 65 have hereunto subscribed my name this 13th day of December, 1921.

ARGYLE CAMPBELL.
